UNITED STATES PATENT OFFICE.

WILLIAM A. FULLER, OF BEAVER FALLS, PENNSYLVANIA.

BROOM-MOISTENER.

No. 921,225.

Specification of Letters Patent.

Patented May 11, 1909.

Application filed May 25, 1908. Serial No. 434,882.

To all whom it may concern:

Be it known that I, WILLIAM A. FULLER, a citizen of the United States, residing at Beaver Falls, in the county of Beaver and State of Pennsylvania, have invented a new and useful Broom-Moistener, of which the following is a specification.

The invention relates to improvements in broom moisteners.

10 The object of the present invention is to improve the construction of brush or broom moisteners, and to provide a simple and comparatively inexpensive moistening device, adapted to be quickly applied to and removed from an ordinary broom, and capable of holding a quantity of water, oil or antiseptic solution and of enabling the discharge of the same to be readily controlled.

20 A further object of the invention is to provide a plurality of discharge channels or passages, arranged to secure a uniform distribution of the contents of the moistener to the broom, whereby an excessive discharge of liquid at a single point is eliminated.

25 With these and other objects in view, the invention consists in the construction and novel combination of parts hereinafter fully described, illustrated in the accompanying drawing, and pointed out in the claims 30 hereto appended; it being understood that various changes in the form, proportion, size and minor details of construction, within the scope of the claims, may be resorted to without departing from the spirit or 35 sacrificing any of the advantages of the invention.

In the drawing:—Figure 1 is a perspective view of a moistening device, constructed in accordance with this invention and shown 40 applied to a broom. Fig. 2 is a rear elevation of the moistening device. Fig. 3 is a vertical sectional view, taken substantially on the line 3—3 of Fig. 2. Fig. 4 is a similar view, taken substantially on the line 4—4 of Fig. 2. Fig. 5 is a longitudinal sectional view, the inner plate being partially broken away to illustrate the arrangement of the channels or passages more clearly.

Like numerals of reference designate corresponding parts in all the figures of the drawing.

1 designates a narrow substantially oblong reservoir, designed to contain water or oil for laying the dust, or an antiseptic solution, and constructed of sheet metal, or other suitable material. The reservoir or receptacle, which is disposed in an approximately horizontal position, when applied to a broom 2, has its front wall 3, its rear wall 4, its bottom 5 and its top 6, constructed from a single piece of sheet metal, which is bent and curved to form the bottom. The end walls 7 preferably consist of separate pieces suitably secured to the contiguous portions of the reservoir at the end edges thereof. The front wall 3 has its upper portion angularly bent and arranged at an inclination to form the top 6, which is equipped with a filling orifice. The reservoir is provided at the filling orifice with a threaded flange 8 for the reception of a screw cap 9 of the ordinary construction. The screw cap is removable to permit the reservoir to be supplied with the desired liquid.

The rear wall is provided with a series of downwardly diverging inclined discharge passages 10, terminating at their lower ends in semispherical nozzles 11, and communicating at their upper ends with a horizontally disposed approximately oblong discharging chamber 12, having inlet passages 13 at the top located at the end portions of the chamber 12 and spaced from the filling orifice, so that there will be no liability of the liquid dropping into the discharging chamber while filling the reservoir. The downwardly diverging passages which are arranged in a vertical plane consist of grooves or channels, formed by stamping the metal of the rear wall of the reservoir and pressing the same outward from the inner face of the said rear wall. The discharging chamber, which tapers downwardly, likewise consists of a depression formed by stamping or pressing the sheet metal outwardly from the inner face of the rear wall, and the grooves or channels are separated into separate passages by means of an inner face plate 14, soldered or otherwise secured to the inner face of the rear wall of the reservoir, and stamped at the upper portion to form the inlet passages 13. The semispherical nozzles 11, which

consist of protuberances, project outwardly beyond the channels or passages and are provided with discharge perforations 15. The projecting nozzle protuberances are adapted 5 to be partially embedded in the straw of the broom so that the liquid contents of the reservoir will be discharged into the same.

The reservoir is mounted on the broom 2 by means of a pair of hooks 16, constructed 10 from a single piece of wire, or other suitable material and piercing the rear wall of the receptacle beyond the upper portions of the passages, and connected by a horizontal portion 17, which operates to bind the face plate 15 14 to the rear wall of the reservoir. In practice the hooks, which extend downwardly from the upper portion of the rear wall of the reservoir at an angle, are embedded in the stitched portion of the broom, and the nozzles or protuberances 11 are located below 20 the said stitched portion.

The flow of the contents of the reservoir through the discharge passages is controlled by the person using the broom. When it is 25 desired to discharge a quantity of liquid contained in the reservoir, the broom is partially raised to tilt or place the reservoir in a horizontal position, so that the liquid will flow through the passages 13 into the discharging chamber 12, from whence the liquid is evenly distributed to the broom through the downwardly diverging discharge 30 passages 10. As soon as the broom is raised sufficiently to raise the upper ends of the inlet 35 passages 13 above the surface of the water, or other liquid the flow of the same to the discharging chamber will be cut off. The flow of the liquid from the reservoir into the discharging chamber is controlled by the operator, and the contents of the reservoir are 40 not permitted to slosh freely into the said chamber while the broom is in its normal position when in use.

Having thus fully described my invention, 45 what I claim as new and desire to secure by Letters Patent, is:—

1. A moistener of the class described including a reservoir, a discharging chamber located at the upper portion of the back of 50 the moistener and separate from and communicating with the interior of the reservoir at the top only so as to be filled by tilting the moistener below the normal position occupied by a broom when in use, and a plurality 55 of discharge passages arranged in a vertical plane and extending from the discharging chamber and having discharge outlets at the bottom.

2. A moistener of the class described including a reservoir, a chamber located at the 60 top of the back of the reservoir and communicating at the top only with the interior of the said reservoir and arranged to be filled

by tilting the moistener below the normal position occupied by a broom when in use, 65 and discharge passages arranged in a vertical plane and each communicating at the top with the discharging chamber and having an individual outlet through the receptacle at the bottom, said passages diverging downwardly and terminating in projecting nozzles. 70

3. A moistener of the class described including a reservoir provided in the inner face of one of its walls with a depression and having a series of grooves or channels extending 75 from the said depression, a plate covering the depression and the grooves and coöperating with the same to form a chamber and discharge passages.

4. A moistener of the class described including a reservoir provided in the inner face of one of its walls with a depression and having a series of grooves or channels extending from the said depression, a plate covering the depression and the grooves and coöperating 85 with the same to form a chamber and discharge passages, said plate being grooved at the top, the inlet passages for the chamber and the reservoir being perforated at the discharge ends of the grooves or channels. 90

5. A moistener of the class described including a reservoir provided in one of its walls with a depression and having a series of grooves or channels extending therefrom, a plate secured to the reservoir and covering 95 the depression and the grooves or channels to form a chamber and a series of passages, and attaching hooks arranged exteriorly of the reservoir and having an interior connecting portion extending across the said plate. 100

6. A moistener of the class described including a reservoir provided at the front with a filling orifice, a discharging chamber arranged at the top of its rear wall and provided at the top with inlet passages spaced 105 from the filling orifice of the reservoir and arranged to be filled by tilting the moistener below the normal position occupied by a broom when in use, and discharge passages communicating with the chamber at the bottom thereof and having outlets through the reservoir. 110

7. A moistener of the class described including a reservoir constructed of sheet metal and provided at the inner face of one of its walls with an upper depression and having a plurality of downwardly diverging grooves or channels extending from the depression, said reservoir being also provided at the lower ends of the grooves or channels with exterior 115 semispherical projections and having perforations in the same to form nozzles, and a plate secured to the interior of the reservoir and covering the depression and the grooves or channels. 120

8. A moistener of the class described pro-

vided with a vertical rear wall and having an inclined top wall extending upwardly from the front of the reservoir to the said rear wall and having an inlet arranged in the angle 5 formed by the inclined top of the reservoir and the rear wall thereof and permitting the discharging chamber to be filled by tilting the moistener below the normal position occupied by a broom when in use, and discharge 10 passages extending downwardly from the

bottom of the discharging chamber and having individual outlets through the reservoir.

In testimony, that I claim the foregoing as my own, I have hereto affixed my signature in the presence of two witnesses.
